LAST

Ernest E. Ouellette, Manchester, N. H.

Application April 22, 1938, Serial No. 203,502

6 Claims. (Cl. 12—136)

This invention relates to lasts for shoes. The upper and other parts of a shoe are built on the last, and, therefore, fit very closely but at a certain stage in the assembling of the shoe, the last must be removed.

To facilitate the removal of the lasts, they are often made with a toe section and a heel section pivoted together so that the shoe heel portion can be released from the last and then the shoe toe portion and the whole shoe can be removed from the last.

Difficulty is experienced because the curve desired in a shoe heel, when considered in a vertical lengthwise plane, is not one which can ordinarily be struck on a center which coincides with the center of the pivot between the toe section and the heel section of the last.

In fact, the heel curve is such that there is a backward bulge and frequently the top and bottom ends are on different slopes or curves. In other words, the heel curve is not a regular arc of a circle.

On account of this, it is often necessary to apply great force to bend the heel part of the shoe in order to remove the shoe from the last.

I use a last of two sections pivoted together on what might be called a sliding pivot. By providing a spring and a stop or stops which preferably may be the adjoining parts of the last, the last is resiliently held in working position. In my preferred construction, the spring is so positioned as to also hold the parts in the open position. To accomplish this, I use a holding spring of the compression type in the toe section which so co-operates with a rigid pivot or connecting plate fixed to and extending from the heel section, preferably with a ball between, that the parts pass a dead center from the working or operative position to the position in which the shoe is being removed from the last, which I will call the open position.

I am aware that complicated arrangements of slots and other devices have been proposed for allowing the heel portion of the shoe to be released from the last but this invention is a very strong, simple arrangement of parts whereby the last is not weakened in any way but can be removed by the simple movement of bending the toe of the shoe and of the last, then pushing the toe parts towards the heel parts and then continuing the bending motion until the heel of the shoe, now being clear of the heel of the last, freely releases itself therefrom.

I so cut the adjoining parts of the heel and toe sections that the sections are held firm-

ly in place in the working position by stops, a pivot and a spring but by three continuous motions they can be released, swung on a pivot and pushed together against the pressure of the spring.

In the drawing, Fig. 1 is a vertical, longitudinal section of a last with the shoe on it, the last being placed on a jack post.

Fig. 2 is a plan view of the same last and shoe resting on its sole and removed from the jack post.

Fig. 3 is a view similar to Fig. 1, showing the first or beginning of the movement to release the shoe heel from the last heel.

Fig. 4 is a fragmentary view of the working position of a modification of the last such as shown in Fig. 1.

Fig. 5 is a view similar to Figs. 1 and 3, showing the next position of the parts in releasing the shoe from the last.

Fig. 6 is a view similar to Fig. 4 of a last showing that modification but with the parts in the open instead of the closed position.

Fig. 7 is a view of the same last shown in Figs. 1, 3 and 5 in the last position where the shoe heel is released from the last.

Fig. 8 is a view similar to Fig. 6 of still another modification of the last.

In the drawing, H represents a shoe with a sole part 41, a toe part 42 and a heel part 43. As shown, the heel part 43 is curved on a double or irregular curve.

J represents the well-known jack post which enters a hole 20 in the heel section A of a last, the heel part 3 of the heel section A corresponding in shape and size with the heel part 43 of the shoe.

B represents the toe section of the last and includes a toe part 2.

The sole part of the last is represented by 1. This in the drawings is shown as at the top, although when the shoe is on the foot, it becomes the bottom.

The other part 11, although shown as at the bottom, I will call the upper part of the last as 45 it is nearest the upper of the shoe.

Extending lengthwise and vertically into the front part of the heel section and into the back part of the toe section are the coinciding slots 4 and 14 and adjoining the sole part are the stop faces 5 and 15 and at the upper or other side are the stop faces 6 and 16. Between the faces 5 and 6 is a concave intermediate front face 7 of the heel section and between the faces 15 and 16 is a convex intermediate back face 17 of the toe 55

section. Preferably between heel front face 7 and face 5 is a heel curve ridge 8 and between toe back face 17 and face 15 is a toe curve ridge 18.

- 5 Ridges 8 and 18 are normally in engagement when the last is in working position and with faces 5 and 15 form the stops or stop faces which hold the sections rigidly together so that the adjoining portions of the sole part of the heel and of the toe will exactly register and so that 10 there will be no slipping between the faces 5 and 15. These ridges might be omitted, however, as shown in Fig. 8.

C is a connecting plate fixed in slot 4 in heel section A by means of pins 30 and 31 and extending out at 32 into slot 14 of toe section B.

- 10 is a straight transverse slot extending through plate C of oblong shape so that pivot pin P which passes through it from toe part B will be allowed to move only in the direction of 20 the axis of slot 10. This axis and movement is at an angle sufficiently great with the stop face 15 to prevent any slipping between it and stop face 5. Preferably, also, there should be a sufficiently large angle between this axis and the face 16 to prevent slipping of that face on stop face 6.

The curves 7 and 17 of the intermediate faces of the heel section and toe section come together at the ridges 8 and 18, but when the last parts 30 are in working position, as shown in Fig. 1, extend away from each other. The axis of the slot 10 passes approximately through intermediate faces 7 and 17 and the bearing end 33 of plate C is engaged by a ball 34 carried by a compression spring S movable in tube T in toe part B. The axis of tube T and spring S is such and ball 34 and end 33 are so related that spring S will hold the sections in the working position on one side of a dead center or in the open position 40 on the other side.

By this arrangement of parts, ordinarily the spring S acting on the end 33 of plate C keeps the last parts A and B firmly together with the stop faces 5 and 15 and ridges 8 and 18 in engagement so that the last can be used in the usual manner in the working position.

The arrangement is such, however, that when the toe parts of the last and shoe are bent down slightly, as shown in Fig. 3, stops including faces 5 and 15 and the ridges 8 and 18 and the curved faces 7 and 17 separate so that, as shown in Fig. 5, when the toe parts are pushed towards the heel parts in the direction of the axis of slot 10, then the shoe heel part 43 moves away from the last heel part 3 and as the bending of the toe is continued, the shoe heel is entirely released, as shown in Fig. 7.

The faces 5 and 15 and 6 and 16 serve as stops to limit the pivotal movements of the heel and toe sections of the last towards and from the working position.

Preferably the angle of the axis of spring S is such that when the last parts are moved, it will hold them in the working position shown in 65 Fig. 1 or in the open position shown in Fig. 7. In Figs. 1 and 2 compression spring S keeps pin P at the toe end of slot 10.

As shown in Figs. 4 and 6, I may use a last with the heel section E and toe section F connected by a pivot plate 28 in which is a slot 29 through which passes a pin 38. A compression spring 39 resiliently holds the sections together. In this case, the front face 25 of heel section E which is next the sole, engages the back face 35 75 of toe section F and there are the ridges 50 and

51, all of which engage when the last is in working position.

When in the open position shown in Fig. 6, the faces 26 and 36 engage. Faces 25 and 26 and 35 and 36, as well as 50 and 51, all serve as stops. 5

The intermediate faces 27 and 37, however, are not curved but are straight. These faces might be of almost any shape, although the curved shape is preferred, as they do not engage.

In fact, as shown in Fig. 8, I can use the heel 10 part G and toe part L connected together by a connecting plate 58 with a slot 59 through which passes a pin 68, there being a spring 69 with no co-operating ridges at all.

Spring 69 rests in recesses 70 and 71 and does 15 not touch the connecting plate 58.

In this construction, when in the working position, the faces 55 and 65 engage and when in the open position, the faces 56 and 66 engage, while the faces 57 and 67 between them are shown 20 as straight, although they might be of almost any shape.

Ridges such as 8 and 18 and 50 and 51 are desirable as a part of the stop devices as they co-operate with the spring to keep the sole parts 25 of the heel and toe sections accurately in line when in the working position.

Instead of the toe section and heel section being released by sliding on each other, I use a single sliding pivot. This pivot includes a single, 30 straight slot instead of two slots or a slot with a turn and instead of a latch for locking the sections in working position, I use the adjoining faces of the sections as stops to co-operate with a pin in the slot and a spring to hold the parts 35 firmly in working position.

The fixed and rigid plate C preferably fits fairly close in the slot 14 and thus prevents side movement, and the ridges 8 and 18 keep the parts, especially the sole, accurately in position, 40 while the spring S holds the parts resiliently together. These facts, together with the important fact that the fixed slot, such as 10 or 59, allows movement in only one direction keep the parts accurately in working position, but permit the 45 toe part to be pushed down and towards the heel, thus releasing the shoe heel.

I claim:

1. The combination in a shoe last comprising a heel section and a toe section pivoted together, there being a stop and a spring to hold the sections firmly in working position and there being a space between the front face of the heel section and the back face of the toe section to permit movement to and from each other when the last is not in working position; of a connecting plate fixed to the heel section and extending into the toe section and having a bearing surface at its end, the connecting plate having a single straight elongated transverse pivot slot; with a holding spring positioned in the toe section and so bearing against the end of the connecting plate as to resiliently hold the sections in working position; and a pivot pin fixed in the toe section and passing through the pivot slot in the connecting plate, the adjoining parts of the heel and toe sections being so shaped that the sections can be moved towards each other along the axis of the slot after the toe section has been started to move on the pivot pin away from the working 70 position.

2. The combination in a shoe last comprising a heel section and a toe section pivoted together, the portions of the front face of the heel section and the back face of the toe section which adjoin the 75

last sole being so formed as stop faces to limit and determine the position of the sections when the last is in working position in a shoe, the portions of said faces which adjoin the last upper being in planes which substantially radiate from a pivot pin and form an obtuse angle with the stop faces, and the intermediate portions of said faces having a space between them when the last is in working position and being so formed that the sections can be moved towards each other after the sections are moved pivotally from the working position; of a connecting plate fixed to one section and extending into the other section and having a single straight elongated pivot slot, the extended axis of which passes through said intermediate face portions and is at a sufficient angle with the stop faces to prevent them from slipping; a pivot pin which passes through said pivot slot; and a spring to hold the sections resiliently together in working position.

3. The combination in a shoe last comprising a heel section and a toe section pivoted together, the portions of the front face of the heel section and the back face of the toe section which adjoin the last sole being so formed as stop faces to limit and determine the position of the sections when the last is in working position in a shoe, and the other portions of said faces having a space between them when the last is in working position and being so formed that the sections can be moved towards each other after the sections are moved pivotally from the working position; of a connecting plate fixed to one section and extending into the other section and having a single straight elongated pivot slot, the extended axis of which passes through said other faces proximate the stop faces and is at a sufficient angle with the stop faces to prevent them from slipping; a pivot pin which passes through said pivot slot; and a spring to hold the sections resiliently together in working position.

4. The combination in a shoe last comprising a heel section and a toe section pivoted together, the portion of the front face of the heel section and of the back face of the toe section which adjoin the last sole being formed as flat stop faces to limit and determine the position of the sections when the last is in working position in a shoe and ending in ridges to prevent slipping of such faces in one direction, the adjoining portions of said front and back faces having a space between them when the last is in working position, such adjoining portions being so formed that the toe section can be moved toward the heel section after the toe section is moved pivotally

from the working position, there being aligned adjoining slots in the heel and in the toe sections; of a connecting plate fixed in the slot in one section and extending into the slot in the other section, said plate having a single straight elongated slot with substantially parallel sides and an axis which when extended passes through such adjoining face portions and is at a sufficient angle with the stop faces to prevent them from slipping; a pivot pin which passes through said pivot slot; and a spring to hold the sections resiliently together in working position.

5. The combination in a shoe last comprising a heel section and a toe section pivoted together, the portion of the front face of the heel section and of the back face of the toe section, which adjoin the last sole, being formed as flat stop faces to limit and determine the position of the sections when the last is in working position in a shoe and ending in ridges to prevent slipping of such faces in one direction, the adjoining portions of said front and back faces having a space between them when the last is in working position, such adjoining portions being so formed that the toe section can be moved toward the heel section after the toe section is moved pivotally from the working position; of a connecting plate fixed to one section and extending into the other section, said plate having a single straight elongated slot with substantially parallel sides, and an axis which is at a sufficient angle with the stop faces to prevent them from slipping; a pivot pin which passes through said pivot slot; and a spring to hold the sections resiliently together in working position.

6. The combination in a shoe last comprising a heel section and a toe section pivoted together, there being a stop and a spring to hold the sections firmly in working position and there being a space between the front face of the heel section and the back face of the toe section to permit movement to and from each other when the last is not in working position; of a connecting plate fixed to the heel section and extending into the toe section, the connecting plate having a single straight elongated pivot slot; and a pivot pin fixed in the toe section and passing through the pivot slot in the connecting plate, the adjoining parts of the heel and toe sections being so shaped that the sections can be moved towards each other along the axis of the slot after the toe section has been started to move on the pivot pin away from the working position.
